(57) **CLAIM**

The ornamental design for a robotic manipulator, as shown and described.

DESCRIPTION

FIG. 1 is a right, front perspective view of my new robotic manipulator design;

FIG. 2 is a right, rear perspective view thereof;

FIG. 3 is a right-side elevation view thereof;

FIG. 4 is a front elevation view thereof;

FIG. 5 is a left, front perspective view thereof;

FIG. 6 is a left-side elevation view thereof;

FIG. 7 is a rear elevation view thereof; and,

FIG. 8 is a top plan view thereof.

The broken dash lines shown in the drawing views represent portions of the robotic manipulator and form no part of the claimed invention.
